(57) CLAIM

The ornamental design for a wing-shaped guitar pick as shown and described.

DESCRIPTION

FIG. 1 is a top front perspective view of a guitar pick with a wing-shaped guitar pick, showing my design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines shown in the drawings depict portions of the wing-shaped guitar pick that form no part of the claimed design.
